DESIGN FOR A COMBINED DOUBLE ENDED JAR AND CAP COVERS THEREFOR OR SIMILAR ARTICLE

Albert Abrams, New York, N. Y.

Application February 24, 1938, Serial No. 75,360

Term of patent 14 years

To all whom it may concern:

Be it known that Albert Abrams, a citizen of the United States and resident of New York city, in the county of Queens and State of New York has invented a new, original, and ornamental Design for a Combined Double Ended Jar and Cap Covers Therefor or Similar Article, of which the following is a specification, reference being had to the accompanying drawing, forming part thereof, in which Fig. 1 is a front elevational view of a combined double ended jar and cap covers therefor or similar article, showing my

new design. Figs. 2 and 3 are top and bottom plan views, respectively, thereof, and Fig. 4 is a perspective view of a double ended jar fitted with closure caps showing the top closure cap raised from its closed position and the bottom closure cap lowered from its closed position.

I claim:

The ornamental design for a combined double ended jar and cap covers therefor or similar article, as shown and described.

ALBERT ABRAMS.
